UNITED STATES PATENT OFFICE.

GIDEON S. ADAMS, OF CAMDEN, NEW JERSEY.

COMBINATION-TOOL.

SPECIFICATION forming part of Letters Patent No. 635,220, dated October 17, 1899.

Application filed March 20, 1899. Serial No. 709,813. (No model.)

To all whom it may concern:

Be it known that I, GIDEON S. ADAMS, a citizen of the United States, residing at Camden, in the county of Camden and State of New Jersey, have invented a new and useful Combination-Tool, of which the following is a specification.

This invention relates to combination-tools, and has for its object to provide a novel arrangement of folding hack-saw connected with the handle of the implement.

To this end the present invention consists in the combination and arrangement of parts, as will be hereinafter more fully described, shown in the accompanying drawings, and particularly pointed out in the appended claims.

In the drawings, Figure 1 is a side elevation of the tool. Fig. 2 is a longitudinal sectional view thereof. Fig. 3 is a front edge elevation showing the hack-saw folded into the handle. Fig. 4 is a detail sectional view of the adjusting-nut.

Corresponding parts are designated by like reference characters in all the figures of the drawings.

Referring to the accompanying drawings, 1 designates the handle of the tool, having at one end the fixed jaw 2, which is formed into 20 a claw 3 at one side and a hammer-head 4 at the opposite side thereof. The hammer-head portion of the jaw is offset to one side of the handle and is provided with an angular passage or opening 5, extending entirely through 30 the offset portion of the fixed jaw and parallel with the handle. Fitted in this passage is the movable jaw 6, which is provided with an angular shank 7, slidably mounted in the said passage, and a threaded extension 8, which is 40 adapted to project beyond the fixed jaw. An adjusting-nut 9 is provided upon the threaded extension of the shank, whereby the movable jaw may be adjusted with reference to the fixed jaw. This adjusting-nut is preferably 45 provided with peripheral radial openings 10 to receive an end of a suitable pin 11, normally carried within the hollow handle and by which the nut may be forcibly turned other than by the grasp of the hand. Extending 50 centrally from the nut is a reduced neck 12, provided upon its outer end with an outer annular flange 13. The neck is received with-

in a lateral extension of the passage 5, and the flange 13 is fitted in slots 14, which are provided through opposite side walls of the passage 5. By reason of the flange 13 resting upon the bottom walls of the opposite slots 14 the nut is held to the jaw, and the said slots are longer than the diameter of the annular flange, whereby the shank of the movable jaw may have a lateral rocking movement when the wrench is first operated to turn the object to which it may be applied.

The engaging face of the fixed jaw is provided with a removable dovetailed block 15, 65 which is bifurcated longitudinally and provided at opposite sides of the bifurcation with teeth or serrations 16 to form a positive gripping-surface for the jaw. Mounted within the bifurcation in the block 15 is a rotary 70 cutting-disk 17, which is journaled upon a split pivot-pin 18, passing transversely through the block. The movable jaw has its engaging face of substantially inverted-V shape and is provided with a slot 19, extending 75 through the jaw in the plane of the handle. Mounted within this slot and projecting beyond the respective angled faces of the movable jaw is a pair of cutting-disks 19^a, which are arranged upon opposite sides of the disk 80 17, carried by the fixed jaw, and with which they are adapted to coöperate and form a pipe-cutter, as will be understood.

As hereinbefore stated, the handle of the implement is hollow and the edge thereof next 85 to the claw 3 is slotted or recessed longitudinally, as at 20, to accommodate the blade 21 of a hack-saw. The opposite ends of the saw-blade are carried by arms 22 and 23, respectively, which are pivoted in the opposite ends 90 of the recess 20, into which the blade is adapted to be folded when not required for use. The arm 23 has one end disposed within the recess 20 and is mounted upon a pivot-pin 24, passing laterally through the handle, and the 95 saw-blade is pivoted to its outer end, as at 25. The arm 22 at the opposite end of the saw-blade is formed by two pieces of metal pivoted within the recess as described for the other arm and receiving the blade between 100 their ends, to which it is pivoted, as at 26. Just beneath the pivot 26 the side pieces of the arm 22 are sprung or bowed outward and are adapted to engage the side walls of the

recess 20 when the saw is folded within the handle and by reason of their binding engagement therewith form a means for holding the saw in its folded position and against 5 accidental unfolding thereof. It will be observed that the recess 20 is enlarged, as at 27 and 28, at opposite ends, respectively, to accommodate the pivotal arms of the saw-blade, and the enlargement 27 forms stop-shoulders 10 27^a, against which the arm 22 is adapted to engage in the unfolded or set-up position of the saw. In advance of the arm 23 is provided a pair of slots or openings 29, aligned transversely of the handle and adapted to 15 receive a wedge-shaped key 30, which is forced across the arm 23 to tighten the blade of the saw and hold the latter from being accidentally collapsed or folded. It will be apparent that as the arm 22 is held fixed by the shoulders 27^a the key 30 will force the arm 23 backward upon its pivot and cause the blade to be tightened.

The handle of the implement is made hollow to accommodate the pin 11 and the key 25 30 when not required for use, and the butt-end of the handle is open and screw-threaded interiorly and adapted to receive a closure-plug 31, having a ring or eye 32, whereby the implement may be conveniently hung up 30 when not required for use. It will be understood that it is not essential to the present invention that the handle be hollow, as the saw-blade is received within the recess 20 and not within the hollowed-out portion of the handle.

35 The present invention provides an exceedingly practical and useful implement or tool combining in its structure a pipe-wrench, a pipe-cutter, a claw-hammer, and a hack-saw, all of which are of durable construction and 40 are conveniently arranged and do not interfere with the proper manipulation of each other. The saw-blade is conveniently housed within the handle when not required for use and may be readily set up in position for use, 45 and the blade thereof is kept under a constant tension to prevent breaking thereof when in use.

Changes in the form, proportion, size, and the minor details of construction within the scope of the appended claims may be resorted to without departing from the spirit or sacrificing any of the advantages of the present invention. 50

Having thus described the invention, what is claimed is— 55

1. In a tool of the class described, the combination with the handle thereof, having a longitudinal recess, of a saw-blade, opposite arms pivoted to the respective ends of the blade and pivotally mounted in the recess, 60 whereby the blade may be folded into the said recess, and locking devices for the arms in the open and closed positions thereof, substantially as shown and described.

2. In a tool of the class described, the combination with the hollow handle thereof having a longitudinal recess formed in one edge and communicating with the interior of the handle, of a saw-blade, opposite arms pivoted to the respective ends of the blade and pivotally mounted in the recess, a stop for one of the arms, and a locking device adapted to be placed transversely against one of the arms, whereby the saw is held in its set-up position, substantially as shown and described. 65 70

3. In a tool of the class described, the combination with the hollow handle thereof, having a longitudinal recess formed in one edge and communicating with the interior of the handle, of a saw-blade, opposite arms pivoted to the respective ends of the blade and within the recess, one of the arms being formed by opposite metal side pieces which are sprung apart or bowed, and adapted to engage the walls of the recess and form a means for holding the saw in its folded position, substantially as shown and described. 75 80 85

In testimony that I claim the foregoing as my own I have hereto affixed my signature in the presence of two witnesses.

G. S. ADAMS.
